UNITED STATES PATENT OFFICE.

MAX RACHLIN, OF NEW YORK, N. Y.

GUTTER HANGER.

Application filed December 10, 1924. Serial No. 754,958.

The present invention relates to improvements in gutter-hangers, that is to say to devices for supporting roof gutters. The invention pertains more particularly to gutter-hangers for use with a gutter having a beaded edge and including a bar portion extending transversely between the upper edges of the gutter, said bar portion being provided at one of its ends with an arched portion designed to be bent around the bead of the gutter.

The main object of the invention is to provide a gutter-hanger of the type mentioned, having means to insure proper bending of the arched portion around and into snug engagement with the bead of the gutter.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages of the invention.

Two of the many possible embodiments of the invention are illustrated in the accompanying drawings, in which:—

Figure 1 is a side elevation of a gutter-hanger constructed in accordance with the present invention, the gutter being shown in position thereon; Fig. 2 is a similar elevation of a portion of the gutter and hanger, on a larger scale; Fig. 3 is a side elevation, also on a larger scale, of a portion of the hanger in its flat state; and Fig. 4 is a section similar to the one shown in Fig. 2 of a modified construction.

Referring now first to Figs. 1 to 3, inclusive, of the drawings, the numeral 10 indicates a roof gutter, the outer edge of which is provided with a bead 11, as usual in constructions of this type, while its inner edge 12, adjacent the wall of the building, is plain. For supporting this gutter in proper relation to the roof of the building, there is provided a plurality of hangers, spaced apart a suitable distance, each of said hangers comprising a strap 13, which surrounds transversely the gutter, and a

roof strap 14, attached to the strap 13 and the roof. The strap 13 is, preferably, made of a single piece of sheet metal, and includes a curved gutter-embracing portion 15, designed to underlie the gutter, and having an arched portion 16 at one of its ends, said arched portion fitting over the bead 11 of the gutter and merging into a bar section 17, which extends horizontally and transversely between the upper edges of the gutter. The opposite end of this bar is bent over the plain edge of the gutter, as shown at 18, and is in engagement with the gutter-embracing portion 15 of the strap. The bar section 17 is comparatively rigid, it being in the form of a channel bar. At the juncture of the arched portion 16 and the gutter-embracing portion 15 is formed a projection 19, which may be obtained, for instance, by stamping out from the arched portion 16 a strip 20 along three of its edges and then bending the said strip, around that edge which is disposed at the said juncture, out of the plane of the arched portion 16, as shown in Fig. 3, and further bending the said strip back upon itself, as clearly shown in Figs. 1 to 3, inclusive, of the drawings. In forming this strip, a slot 21 is provided in the arched portion 16 adjacent the said juncture, the said slot somewhat weakening the said arched portion, for a purpose hereinafter to be described.

The gutter hanger is furnished to the trade in a flat state. When the hanger is to be applied to the gutter, the projection 19 is first engaged with the free edge 22 of the gutter bead, the hanger taken hold of by the comparatively rigid bar section 17, and the arched portion 16 bent around and into snug engagement with the bead of the gutter, the bend 18 being then engaged with the plain edge 12 of the gutter. Thereafter the gutter-embracing portion 15 is bent to underlie the gutter, its free edge being engaged with the bent portion 18 of the bar section 17. In bending the arched portion around and into snug engagement with the bead of the gutter, the projection 19 serves as a fulcrum. The slot 21 in the arched portion 16 promotes the forming of the arched portion.

The modification illustrated in Fig. 4 of the drawings differs from the one above described in that the projection 19' at the juncture of the arched portion 16 and the gutter-embracing portion 15 is obtained by means

of a punch or other suitable tool, by which the material of the hanger at and around the said juncture is forced outwards, to form a projection. Otherwise the construction and operation of the elements are the same as of those described in connection with the device illustrated in Figs. 1 to 3, inclusive, of the drawings.

What I claim is:—

10. A gutter hanger for use with a gutter having a beaded edge, comprising a rigid portion extending transversely between the upper edges of the gutter, an arched portion at one end of said rigid portion designed to be bent to snugly fit around the bead of the gutter, a gutter-embracing portion joined with said arched portion designed to under-

lie the gutter, the free end of said gutter embracing portion being engaged with said rigid portion, and a projection formed at 20 the juncture of said gutter-embracing portion and said arched portion, said projection extending only through part of the width of said gutter embracing portion and being adapted to be engaged with the free 25 edge of the bead of the gutter, said projection being disposed, when the hanger is mounted on the gutter, wholly outside of the bead of the gutter, substantially as and for the purpose specified.

Signed at New York, in the county of New York, and State of New York, this 9th day of December, A. D., 1924.

MAX RACHLIN.
